UNITED STATES PATENT OFFICE.

FREDERICK CURTIS, OF BOSTON, ASSIGNOR TO THE HODGES EDGE TRIMMING AND SETTING MACHINE ASSOCIATION, OF LYNN, MASS.

IMPROVEMENT IN MACHINES FOR BURNISHING THE EDGES OF SOLES OF BOOTS AND SHOES.

Specification forming part of Letters Patent No. 130,109, dated August 6, 1872.

Specification describing certain Improvements in Machinery for Burnishing the Edges of the Soles or Heels of Boots and Shoes, invented by FREDERICK CURTIS, of Boston, in the county of Suffolk and Commonwealth of Massachusetts.

These improvements are allied more or less closely to the principle of a machine for like purposes shown and described in Letters Patent of the United States numbered 117,287, and issued to Samuel H. Hodges, of Lynn, Massachusetts, on the 25th day of July, 1871—that is to say, my present machine comprises, like that, the elementary features of a jack or device for supporting the boot, and the combination therewith of mechanism for supporting and operating a burnishing-tool, so organized that said tool, whether itself, the jack, or both, move with a resulting polishing action upon the sole or heel edge.

Heretofore, in machinery for setting sole-edges the burnishing-tool has been a rotary one, but I have found that for certain grades of work, and the better to adapt the tool to the irregular curvature and angle of the sole or heel, a reciprocating or vibratory motion of the tool is preferable; and in order to carry out the purposes of my invention by so adapting said burnishing-tool that while traveling about the circumference of the sole it shall act thereupon with a reciprocating or vibratory motion I have devised the following mechanism, in which I have so arranged details as to instantly bring into action either a tool which reciprocates to and fro of a right or curved line, or vibrates upon its own pivot, or both reciprocates and vibrates, substantially as hereinafter explained, the novelty in the invention consisting in the adoption, in connection with a boot-supporting jack, of a burnishing-tool so mounted as to act upon the entire sole-edge with polishing effect, resulting from a reciprocating or vibratory, or compound reciprocating and vibratory motions. To this end, and in pursuance of the object of my invention in one manner in which the same may be effected, I employ, as herein shown, first, a jack of proper construction for supporting the boot or shoe and advancing to the immediate vicinity of the burnishing or "setting" tool; and, second, a burnishing-tool swiveled upon a carriage which either slides

to and fro of an oscillating swinging beam or frame and causes the said tool to reciprocate in a given plane, or remains stationary upon such beam while the tool vibrates upon the pivot which unites it with the carriage, a compound connecting-rod or series of connecting-rods and levers being so combined with the carriage and with a suitable crank-motion and connected with a hand-lever which operates upon the said carriage that by a turning of said lever either a reciprocating, vibratory, or compound motion may be imparted to the tool, as circumstances or desire may dictate.

The drawing accompanying this specification represents, in Figure 1, a plan; in Fig. 2, a side elevation; in Fig. 3, a front-end view of a machine embodying my invention. Fig. 4 is an opposite side view of the oscillating beam G, to be explained.

The drawing accompanying this specification represents, at A, a jack of any suitable character for properly supporting a boot or shoe while the sole of the latter is being operated upon, this jack being mounted in an adjustable manner upon the top of a curved standard, B, which standard is in turn swiveled upon the top of a table or platform, C, duly supported upon the top of two swinging or rocking standards, D D, whereby the jack and the boot carried by it may be advanced to or removed from the burnishing-tool. In rear of the rocking table C I erect, upon the floor of the apartment containing the machine, or upon the base of such machine, two upright standards, E E, and between these standards I mount an upright swinging or rocking standard or frame, F, to the upper part of which frame I pivot, by a stud, a, a horizontal, flexible, or swinging arm or beam, G, which projects forward toward the jack, this beam being balanced or overbalanced in any suitable manner in order to relieve the operator of the labor of supporting its weight, the standard E being provided with oppositely-disposed springs H H or their equivalents, whereby it is held in any position in which it may be left. The burnishing or setting tool is shown at c in the drawing as an oblong bar pivoted practically at about its center to one side of a grooved block or carriage, d, which is mounted upon the outer end of the beam G before named, the lower end of the said bar being

fashioned into the requisite form to obtain the desired outline to the sole-edge. In order to vibrate or rock the tool *c* upon its pivot while the carriage *d* is stationary or reciprocating with short intermittent movements, I fulcrum at about its center a long upright lever, *e*, to the side of the standard *E*, the oscillations of this lever upon its fulcrum *f* being induced by connecting its lower end to the wrist-pin *g* of a crank or crank-wheel, *h*, affixed to the end of a horizontal shaft, *i*, mounted in a suitable standard, *j*, erected between the standards *E* and *E* before named, the upper end of the said lever being connected to the rear end of a pitman, *k*, which lies alongside of the beam *G* and follows its vertical swinging motions. The front end of the pitman *k* is fashioned into a link-head, *l*, formed with an upper and lower link, *m* and *n*, the former of which embraces at all times a lateral stud, *o*, projecting from the adjacent side of the upper end of the bar or tool *c*, while the lower link *n* operates in connection with a second lateral stud, *o'*, projecting from the opposite side of the tool *c* to embrace, when lowered, said stud *o'*, and when elevated to be removed from contact therewith. Upon the opposite side of the carriage *d* I form or apply a fork or recessed plate, *p*, the opening *q'* of which expands at its upper part, while in front of this fork I pivot, by a stud or journal, *a'*, to the front end of the beam *G*, the front extremity of an arm, *q*, the rear extremity of such arm bearing a lateral stud, *r*, which coincides with and enters, when depressed, the fork *p*, and either locks the carriage *d* to the beam *G* or compels it to reciprocate in very short movements thereupon, according to which part of the flaring recess *q* the stud remains in, the pivot of the arm *q* being provided with a knob or handle, *s*, by which the operator may instantly and readily elevate or depress its free end, and thus adjust the position of the carriage *d* upon the beam *G*. In order that, with the descent of the arm *q* in the act of partially or entirely locking the carriage *d* to the beam *G*, as last stated, the link *n* shall be elevated from contact with the stud *o'*, and thus permit the vibration of the lever *e* through the agency of the pitman *k* to reciprocate the said carriage *d* upon the beam *G*, I make use of the following compound-lever motion—that is to say, I affix to the outer end of the stud *a'* an upright arm, *t*, to the upper end of which arm I pivot one extremity of a pitman, *u*, the opposite termination of which is pivoted to the lower end of an arm, *v*, which is affixed to and depends from a horizontal transverse rock-shaft, *w*, mounted in the upper part of an upright post, *x*, erected upon the beam *G* at about its center, while to the opposite end of such rock-shaft I affix a horizontal arm, *y*, to the rear or free end of which arm I pivot the upper extremity of an upright link or pitman, *z*, the lower end of this pitman *z* being pivoted to the pitman *k*, before named, at about the center of the latter.

The above constitutes the mechanical ele-

ments of a machine for carrying out in one manner the purpose of these improvements. The variable transverse movements of the jack are for the purposes, as before stated, of advancing the work to the burnishing-tool, while the longitudinal and vertical freedom of motion of the standard *e* and beam *G* are for the purpose of presenting the burnishing-tool to the sole-edge and compelling such tool to travel about the entire circumference of such sole or of the heel, the motions of the burnishing-tool, whether vibratory, reciprocating, or compound, acting upon the leather with the proper polishing action.

If desirable, however, the lateral motions may be imparted to the beam *G* in lieu of the jack, and the latter swing backward and forward; and for this purpose the arm *G* may be applied to the standard *E* by means of a ball-and-socket or other joint.

The operation of the details of mechanism which connect with and actuate the burnishing tool is as follows: If the operator desires a vibratory or compound motion of the burnishing tool he seizes the knob *s*, and, by means of it, depresses the arm *q* and lowers the stud *r* of the latter into the flaring opening *q'* of the forked or recessed plate *p'* before named as constituting part of the carriage *d*, thus locking the said carriage rigidly to the beam *G*, or allowing it to reciprocate thereupon with very short reciprocations, according to the depth with which the stud *r* enters the opening *q'*, it being understood that such stud is of a size to entirely fill the lower termination of said opening in order to effect the said rigid connection. Simultaneously with the descent of the arm *q* and the partial or entire locking of the carriage *d* to the beam *G*, as last stated, the head of the pitman *k* is elevated and its link or notch *n* removed from contact with the stud *o'*, this elevation of the pitman being effected by the arm *t*, pitman *u*, arm *v*, shaft *w*, arm *y*, pitmen *z* and *k*, and lever *e*, hereinbefore explained, in manner as will at once be apparent to the observer. If a reciprocating motion of the burnishing-tool to and fro of the beam *G* is desired the operator has only to remove the motion of the knob or handle *s*, which has the effect, through the agency above named, of freeing the arm *q* from the carriage *d*, thus allowing the latter to slide upon the beam *G*, and, at the same time, of depressing the pitman-head *l* and compelling it to embrace tightly both studs *o o'* of the tool *c*, by this means locking the latter rigidly to the carriage and forcing it to travel with it, as, by this depression of the pitman-head, the oscillating-link motion becomes, by the change of position of the arm *q*, transformed into a rigid connection, which, as stated, compels the carriage, freed from the control of such arm, (which confined it to the beam,) to traverse the latter with intermittent reciprocations.

The burnishing-tool *c* can be made in various forms—as, for instance, both its ends, in its present general shape, may be wrought into

the desired polishing-surface; or it may be a many-sided block, bearing upon one or all its faces the desired configuration in varied sizes or character.

I do not, in any sense, limit myself to the herein-described details of mechanism for imparting the desired motions to the burnishing-tool, as these may be varied to a very great extent by any good mechanic without departing from what I believe to be the novel features in my invention, which is the employment, in a machine for traversing and polishing the edge of boot and shoe soles, of a tool to which reciprocating, vibratory, or compound motions may be imparted.

I therefore claim as of my exclusive invention the following, to wit:

1. In machinery for traversing and burnishing or "setting" the edges of boot and shoe soles, a burnishing or setting tool to which reciprocating, vibratory, or compound motions are imparted, substantially in manner and to produce results herein stated.

2. The combination, with the boot support or jack for holding the work and presenting it to

the burnisher, of a burnishing-tool carried by a flexible or jointed frame, and arranged and operated so as to have imparted to it reciprocating, vibratory, or compound motions, substantially as and for the purposes herein shown and described.

3. In machinery for burnishing sole-edges, the combination, with the burnishing-tool, whereby the movement of said tool may be changed expeditiously from a vibratory to a reciprocating motion, or vice versa, as set forth.

4. The combination of the beam G, carriage d, tool e, pitman k with its head l fashioned as stated, and the arm q, the arrangement and operation of such parts being substantially as hereinbefore stated.

5. In combination, the standard E, beam G, carriage d, and the pitman k, and arm q, or their equivalents, essentially as and for the purposes stated.

FRED. CURTIS.
